UNITED STATES PATENT OFFICE

ORREN I. MASSEY AND CARROLL C. MASSEY, OF ELK CITY, OKLAHOMA

HAT HOLDER

Application filed February 7, 1927, Serial No. 166,396. Renewed May 27, 1930.

The invention relates to hat holders particularly adapted for use in automobiles adapted to be secured to any portion of the automobile, however preferably to the upper 5 inner side of the top, for instance to one of the bows, and is provided with oppositely disposed hat receiving loops formed from spring material, which may be easily pulled downwardly for inserting a hat.

10 A further object is to form both loops from a single piece of spring wire having connecting arms in parallel relation and which arms extend through spaced rolls of a securing plate which plate is attached to a support.

15 A further object is to provide the spaced connecting arms adjacent the inner sides of the hat receiving loops with downwardly offset U-shaped bends which receive the brim of a hat when the crown of the hat is passed 20 through the loops.

25 A further object is to provide the connecting arms between the U-shaped offset portions and the adjacent ends of the rolls with a plurality of convolutions, which convolutions act as springs for increasing the spring 30 action of the loops when they are pulled downwardly thereby allowing a great range of movement to the loops when placing hats therein.

35 A further object is to space the loops and proportion the connecting arms of the loops whereby pairs of loops may be placed in crossed relation if desired.

40 With the above and other objects in view the invention resides in the combination and arrangement of parts as hereinafter set forth, shown in the drawing, described and claimed, it being understood that changes in the precise embodiment of the invention may be 45 made within the scope of what is claimed without departing from the spirit of the invention.

In the drawing:

45 Figure 1 is a perspective view of the hat holder showing the same applied to the underside of a bow.

50 Figure 2 is a transverse sectional view through the bow and a longitudinal sectional view through the plate.

Figure 3 is a vertical transverse sectional view through the plate.

Figure 4 is a bottom perspective view showing crossed plates secured by a single screw.

Referring to the drawing, the numeral 1 55 designates the bow of a conventional form of automobile top, to the underside 2 of which is secured by means of a screw 3 a plate 4. The opposite sides of the plate 4 are provided with rolls 5 through which extend the 60 connecting arms 6 of the oppositely disposed hat receiving loops 7, which are disposed at opposite sides of the bow 1. Rolls 5 are securely clamped on the connecting arms 6 as clearly shown in Figure 3, and it will be 65 seen that the plate 4 is in the plane of the side of the rolls 5 where it will be flat on the bow 1, and through which plate the securing screw 3 extends. The outer ends of the arms 6 are provided with a plurality of convolutions 6a which allow a relatively wide range 70 of flexibility to the hat receiving loops 7 when they are pulled downwardly, and the loops 7 terminate in outwardly extending arms 8 in parallel relation and which arms 8 are in the 75 planes of the loops 7 and are connected to said loops by downwardly extending U-shaped members 9, which downwardly extending U-shaped members 9 receive the hat brim when the crown thereof is passed 80 through the loops 7, and when the loops are released by the operator after placing a hat therein they will move upwardly to a horizontal position. The loops 7 and their connecting arms 6 are preferably formed from 85 a single piece of wire or rod material and may be covered if desired, however applicant does not limit himself to a covering, and it is also to be understood a bag may be carried by the loops 7 if desired. 90

Referring to Figure 4 wherein a bottom perspective view is shown of the plates 4 in crossed relation, said plates are held in crossed relation by a single securing screw 3a, and it will be noted the connecting members connecting the loops 7 are sufficiently long to allow this arrangement, thereby allowing four hats to be held adjacent each other. 95

From the above it will be seen that a hat 100

holder is provided which is particularly adapted for use in automobiles, and the hat holder is simple in construction, may be easily and quickly applied to a conventional form of automobile by a single screw and the convolutions 6^a in the arms 6 allow a relatively wide range of flexibility to the device, thereby allowing a hat to be easily and quickly placed therein. It will also be seen that the device is formed from two pieces of material, therefore it will be seen the device may be cheaply manufactured and sold.

The invention having been set forth what is claimed as new and useful is:—

- 15 A hat holder, said hat holder comprising a plate, a support to the underside of which said plate is secured, spaced rolls at opposite sides of said plate in parallel relation, horizontally disposed arms extending through said rolls, a plurality of convolutions at the ends of said arms in spaced relation to the opposite sides of the support and ends of the plate, hat receiving loops in a plane of the arms, said loops being connected to said arms by means of downwardly extending U-shaped members, said horizontally disposed arms, their convolutions, loops and U-shaped members being formed from a single piece of wire bent to form,
- 20
- 25
- 30 In testimony whereof we hereunto affix our signatures.

ORREN I. MASSEY.
CARROLL C. MASSEY.
